UNITED STATES PATENT OFFICE

CORNELIUS EVAN JOHNSON AND WILLIAM H. EDWARDS, OF GRAND RAPIDS, MICHIGAN, ASSIGNORS TO GRAND RAPIDS LOOSE LEAF BINDER COMPANY, OF GRAND RAPIDS, MICHIGAN, A CORPORATION OF MICHIGAN

LOOSE LEAF BINDER

Application filed July 13, 1931. Serial No. 551,928.

The present invention relates to loose leaf binders and; its object is, generally, to provide an improved device of that character which may be very economically manufactured; and more particularly, to provide in such a device a binding post having improved means for relatively adjusting its members longitudinally and for mounting the post; and further, to provide improved locking means for the binding post.

These and any other and more specific objects hereinafter appearing are attained by, and the invention finds preferable embodiment in, the device particularly described in the body of this specification and illustrated by the accompanying drawing, in which:—

Figure 1 is a sectional view of a loose leaf binder with the leaf body therein, taken on line 1—1 of Figure 2;

Figure 2 is a sectional view thereof taken on line 2—2 of Figure 1;

Figure 3 is a top plan view of means for locking the binding post of the device;

Figure 4 is a sectional view thereof and of the binding post, taken on line 4—4 of Figure 3; and

Figure 5 is a view in perspective of the binding strips, the binding posts and one of the locking means, shown disassembled.

In the drawing is illustrated a loose leaf binder having covers 1 connected by a flexible back 2 on whose inner sides respectively are mounted the flap portions 3 of the binding strips 4, 5. These binding strips are desirably made of thin but rigid and tough material of such character that openings therethrough for the binding posts 6 and the spurs 7 of the post-locking means may be readily and easily made at any desired points corresponding in position with the perforations 8 of the particular leaf body 9 which the binder is to contain.

Each of these binding posts designated generally 6 comprises a tubular member 10 having an end 11 internally threaded at 12, and a member 13 internally threaded at 14 extending into the open other end 15 of the member 10. A screw 16 is threaded in the end 11 of member 10 and also in the member 13, and has a head 17 clamping the binding

strip 5 between it and the end 11 of member 10.

It will be seen that this screw 16 serves the double purpose of longitudinally adjusting the members 10, 13 to the thickness of the leaf body, and of securing the binding post to the binding strip 5.

Means for locking the free end 18 of the binding post on the binding strip 4 comprises a flat slidable bolt 19 and a bearing member 20 therefor made of sheet metal bent to form a base portion 21 mounted on the outer side of the binding strip 4, and a top portion 22 having in its inner side a recess 23, said base and top portions being connected by the 65 right portions 24.

The binding strip 4 and the base portion 21 have openings 25, 26 respectively therethrough registering with the recess 23 as seen in Figure 4. The bolt 19 has a slot therethrough comprising an enlarged portion 27 adapted in one slid position of the bolt to receive the free end 18 of the binding post inserted into said openings 25, 26 and into the recess 23 of the top portion 22, said slot comprising also a narrow portion 29 whose edges in another slid position of the bolt engage in the lateral recess 30 of the free end of the post to lock the post to the binding strip 4.

The bolt has a second slot 31, parallel with its aforesaid slot, and the top portion 22 has a tongue 32 struck downwardly thereinto, thus providing an additional bearing for the sliding movement of the bolt. It will be seen that by reason of these slide bearings and by the free end of the post engaging in the openings 25, 26 under the bolt and in the recess 23 above it, the post is securely held upright in slid positions of the bolt and during its sliding movement.

The spurs 7 of the locking device are inserted into the slits 33 of binding strip 4 which slits may be readily made at desired points as the openings 25 are made, or these pointed spurs may be thrust through said binding strip in the absence of pre-formed slits, and being bent over on the under side of said strip, securely mount the locking means thereon.

The invention being intended to be pointed out in the claims, is not to be limited to or by details of construction of the particular embodiment thereof illustrated by the drawing 5 or hereinbefore described.

We claim:

1. In a loose leaf binder: a pair of binding strips adapted to clamp the leaf body between them; a binding post comprising a tubular 10 member having an internally threaded end, and an internally threaded member releasably secured to one of said strips and extending into the open other end of said first-mentioned member; a screw threaded in the internally threaded end of said first-mentioned member and also in the second-mentioned member, said screw extending through the other binding strip and having a head clamping the same between said head and the internally threaded end of said first-mentioned member.
2. In a loose leaf binder: a pair of binding strips adapted to clamp the leaf body between them and to be readily perforated at desired 25 points to receive the hereinafter-mentioned post; a binding post comprising longitudinally adjustably connected members extending through perforations in the binding strips respectively, one of said members being mounted on one of said strips; a locking device adapted to releasably engage the other one of said members and having spurs adapted to be thrust through the other binding strip for securing said device thereto.
3. In a loose leaf binder: a pair of binding strips adapted to clamp the leaf body between them, one of said strips having an opening therethrough; a binding post secured at one 30 end to the other strip and having a lateral recess adjacent its free end; locking means comprising a slideable bolt and a bearing member therefor made by bending a metal sheet to form a base portion mounted on the outer side of the first-mentioned strip and having an 35 opening therethrough, a top portion having in its inner side a recess registering with said openings, the bolt having a slot therethrough comprising an enlarged portion adapted to receive in one slid position of the bolt the free 40 end of the post inserted into said openings and into said top portion's recess and a narrow portion engaging in the post's recess in another slid position of the bolt to lock the post to the first-mentioned binding strip, the 45 bolt having a second slot and said top portion having a tongue struck downwardly thereinto providing an additional bearing for the sliding movement of the bolt.

In testimony whereof we have hereunto set 50 our hands at Grand Rapids, Michigan, this 3rd day of July, 1931.

CORNELIUS EVAN JOHNSON.
WILLIAM H. EDWARDS.
